US0D1049575S

(12) **United States Design Patent** (10) Patent No.: **US D1,049,575 S**
(45) Date of Patent: ** Nov. 5, 2024

(54) **SLIPPER**

(71) Applicant: **YANGZHOU WUSHE ELECTRONIC BUSINESS CO., LTD.**, Yangzhou (CN)

(72) Inventor: **Qingrong Tang**, Yangzhou (CN)

(73) Assignee: **YANGZHOU WUSHE ELECTRONIC BUSINESS CO., LTD.**, Yangzhou (CN)

(**) Term: **15 Years**

(21) Appl. No.: **29/944,745**

(22) Filed: **May 30, 2024**

(51) LOC (14) Cl. **02-04**

(52) U.S. Cl.

USPC **D2/919**; D2/897

(58) **Field of Classification Search**

USPC D2/896, 897, 899, 900, 902, 904, D2/906-908, 916-924, 925-945, D2/947-960, 969-979
